United States Patent Office

Des. 193,969
Patented Nov. 6, 1962

193,969

BELT

Frank W. Lawson, 5615 Lowell, Indianapolis, Ind.

Filed Nov. 24, 1961, Ser. No. 67,685

Term of patent 14 years

(Cl. D3—10)

FIG. 1 is an isometric view of a belt embodying my new design and showing in dotted lines for purposes of illustration only an accessory case mounted thereon; and

FIG. 2 is an isometric view of the belt shown in FIG. 1 with the case detached therefrom.

I claim:

The ornamental design for a belt, as shown and described.
